UNITED STATES PATENT OFFICE.

HERMAN RUDOLF SACK, OF PHILADELPHIA, PENNSYLVANIA, ASSIGNOR TO RADCLIFFE B. MILLS, OF PHILADELPHIA, PENNSYLVANIA.

MECHANISM FOR TRANSFERRING HAIRS.

1,153,522.

Specification of Letters Patent. Patented Sept. 14, 1915.

Application filed March 19, 1913. Serial No. 755,474.

To all whom it may concern:

Be it known that I, HERMAN RUDOLF SACK, a citizen of the United States, residing in Philadelphia, Pennsylvania, have invented certain Improvements in Mechanism for Transferring Hairs, of which the following is a specification.

The chief object of my invention is to successively and rapidly deliver objects such as horse hairs, bristles or the like to a grasping or conveying means such for example as between two rollers which rotate in opposite directions; the hairs etc. being moved between the said rollers and to be conveyed by the latter to be used for any purpose.

Another object is that mechanism constructed in accordance with my invention will be positive in its operation and will be capable of delivering individual or groups of hairs or the like as above stated; the delivery means being movable at a speed which may be relative to the speed of the grasping or conveying means so that my invention is particularly serviceable for use in the twisting of hairs or bristles as above mentioned, and it can also be advantageously employed for braiding or winding purposes.

A still further object of my invention is to construct a mechanism of the above described type which will be capable of delivering shorter hairs to a grasping or conveying means than has heretofore been accomplished.

These objects, and other advantages which will be set forth hereinafter I attain in the following manner; reference being had to the accompanying drawings in which,

Figure 1, is a sectional side elevation of mechanism constructed in accordance with my invention; Fig. 2, is a plan view of the mechanism shown in Fig. 1; Fig. 3, is a section on the line *a—a* Fig. 1; Fig. 4, is an enlarged sectional view taken on the line *b—b* Fig. 1; Fig. 5, is an enlarged view of the portion of the mechanism shown in Fig. 1 when the same has been moved to convey the end of a hair between two rollers; Fig. 6, is a view of similar nature to Fig. 5 showing the said hair having been grasped and moved therebetween; Fig. 7, is a sectional view on the line *c—c* Fig. 5; Fig. 8, is an enlarged view of a similar nature to that shown in Fig. 1 but showing means whereby a predetermined number of hairs

may be delivered to the said rollers; Fig. 9, is a section on the line *d—d* of Fig. 8; Fig. 10, is a fragmentary view showing a different position of certain of the elements shown in Fig. 9; Fig. 11, is an elevation view partly in section of a modified form of my invention; Fig. 12, is a plan view of the mechanism shown in Fig. 11; Fig. 13, is a view showing another modified form of my invention; and Fig. 14, is a view showing two frusto-conical rollers which I may employ.

Referring to the drawings, 1 is a container or hopper which is preferably arranged so that its bottom is at an inclined angle to two rollers 2 and 3 which are rotatably supported by a bearing 4 which may form a part of the frame of a machine or consist of an independent rigid supporting bar, according to the nature of the mechanism to which my invention is adapted. The rollers 2 may be rotated in the directions indicated by the arrows thereon in Fig. 3 by any well known means, and as illustrated by means of a pulley 5 and intermeshing gears 5^a and 5^b. The rollers 2 and 3 may both be driven by a positive means (or one of the rollers such as the roller 2 may be rotated by a positive means and cause the roller 3 to rotate by frictional contact) in a manner hereinafter more fully described and as illustrated in the several views of drawing.

A cylinder or casing 6 extends within the hopper 1 and is rigidly connected thereto by means of a bracket 7; the latter being screwed or otherwise secured to the said hopper 1 as clearly shown in Figs. 1, 2 and 4. The bottom of the hopper 1 is preferably formed by means of two inclined converging surfaces 8 so that horsehairs, bristles, etc. placed within the said hopper will tend to move down the inclined surfaces 8 to the extreme bottom of the said hopper. A slot 9 is formed within the extreme bottom of the hopper and extends from a point 10 to a point 11; the point 11 being slightly in advance of the surface 12 which acts as a bottom or stop for the lower ends of the hairs, etc. while within the hopper so that there is a shoulder 13 formed which normally prevents the lower end of any of the hairs within the bottom portion of the hopper from dropping through the said slot 9 (see Figs. 1, 5, 6 and 8); the length of the

slot 9 being less than the length of the hairs within the hopper.

I preferably provide the casing 6 with an extension or hair-guiding and gage shoe 14 to guide a predetermined number of hairs into alinement with the slot 9 and to prevent the hairs from becoming tangled as will be more fully discussed hereinafter.

The casing 6 forms a housing for a reciprocable plunger 15 which is recessed at 16 at its lower end; said recess preferably corresponding to the contour of a hair or the like. The plunger 15 is, as illustrated, provided with an extension 17; the latter being substantially square in cross section and movable within a correspondingly square guideway within the cylinder 6 so that the plunger 15 cannot rotate during its reciprocating action within the said cylinder 6 and therefore the recess 16 will always be in a position that when it is moved into contact with a hair, as hereinafter more fully described, the recessed contour will register with the contour of the hair as shown in Figs. 5, 7 and 10. The plunger 15 may be actuated by any mechanical means and as illustrated the same consists of the eccentric 18 on the pulley 19 which is driven by means of a belt 20 and an eccentric strap 21 on the eccentric 18 and being pivotally connected at 22 to the extension 17 on the plunger.

It will thus be seen that, owing to the inclined surface 8 of the hopper, hairs placed within the hopper will tend to successively move into the position occupied by the hair 23 which, as will be noticed, is directly over and in longitudinal alinement with the slot 9. Therefore, as the pulley 19 rotates, the plunger 15 will receive a reciprocating action and tend first to move from the position shown in Figs. 1 and 4 to the position shown in Fig. 5 which is sufficient to push the end of the hair 23 through the slot 9 and between the two rotating rollers 2 and 3, and as the point 10 is preferably directed over the rollers 2 and 3, the hair will be drawn in the direction of the arrow Y Fig. 5, due to the rotation of the said rollers, into the position shown in Fig. 6 and the continued rotation of the said rollers will tend to pull the hair through the slot 9 and out of the hopper in the direction of the arrow Y' Fig. 6 and convey it for any purpose in which the hair is to be employed, and for example as heretofore stated to be twisted, braided, or the like.

When I desire to successively deliver a predetermined and only a predetermined number of hairs to the rollers I preferably construct my mechanism as shown in Figs. 8, 9 and 10 and as illustrated in the said latter figures the construction is such as to deliver one and only one hair at a time between the rollers. In this case I employ a

divider or separator 24 having its lower end formed by two converging surfaces terminating in a point 25. This separator is pivotally secured at 26 to an arm 27; the latter being pivotally mounted at 28 to a standard 70 29 rigidly secured to the hopper and is also slotted at 30. A pin 31 is eccentrically located on the supporting shaft 32 of the pulley 19 and extends within the slot 30 so that the rotation of the said pulley and shaft will cause oscillatory movement to be imparted to the arm 27 and the reciprocating movement to be imparted to the separator 24. However, the movement of the separator 24 will be less extensive than the movement of the plunger 15 and the arrangement is such that when the plunger 15 descends and moves the hair 23 between the rollers 2 and 3, as shown in Fig. 10, the end 25 of the separator 24 will be raised to a 85 position out of engagement with any of the hairs and thereby allow the hairs to move transversely toward the plunger 15 (Fig. 10). However, as soon as the plunger 15 raises to a point which is near its extreme 90 upward position, the point 25 of the separator 24 will descend and pass between the two hairs which are nearest the plunger, and as the latter finishes its upward movement the hair which was closest the plunger 95 will be forced directly beneath the plunger and over the slot 9 and in a position similar to that occupied by the hair 23 in Fig. 9. In using this latter construction whereby the separator is employed I preferably provide the hopper with a series of ribs 33 spaced apart throughout the length thereof, each of which has a curved or inclined edge 34 which support the hairs and tend to move them toward the separator and plunger as heretofore stated. In this case I may also provide the cylinder with an extension similar to 14, if so desired, but the bottom edge 6^a acts as a guiding means so as to prevent congestion or entanglement of the 110 hairs.

In the modifications shown in Figs. 11 and 12 the hopper and rollers are substantially the same as shown in Fig. 1, but instead of using the housed plunger 15, the plunger is in the form of an arm 35 which is secured to a rock shaft 36; the latter passes through or is otherwise supported within the hopper 1. A crank arm 37 is secured to the rock shaft 36 and a link 38 is connected 120 to the crank arm 37 and may be reciprocated by any mechanical means so as to move the arm 35 from the position shown in full lines Fig. 11 to the position shown in dot-and-dash lines. Also, I preferably make the 125 free end of the arm 35 angular as shown at 39 and recess the same as shown at 40 (Fig. 12) so as to correspond with the contour of the hair and similar to the recess 16 in the plunger 15. In this case I may mount a 130

guide 14^a by suspending the same from the sides of the hopper so as to perform a function similar to the guide 14, and so as to keep a predetermined number of hairs below the arm 35 so that when the same is oscillated by the movement of the link 38 and crank 37 the arm 35 will contact with and push the desired number of hairs between the rollers 2 and 3 and so as to be gripped and conveyed by the latter in a manner heretofore described.

It will thus be seen that with the aid of my invention, hairs, bristles, fibers, or the like may be quickly and successively delivered to a grasping or conveying means for any purpose desired.

With the form of rollers shown in Fig. 14 I obtain means for varying the speed by which the hairs are moved from the position shown in Fig. 5 to the position shown in Fig. 6; for example, if the frusto-conical rollers shown in Fig. 14 are substituted for the cylindrical rollers shown in the other views of drawing the result is that if the hairs are delivered to the narrow ends of the rollers as indicated at *x* Fig. 14 the hair will tend to increase its speed as it moves from the narrow ends of the rollers to the position occupied in Fig. 6, owing to the fact that the diameters of the rollers increase from the smaller ends to the larger ends. On the other hand, if the hairs are delivered to the rollers at the point *y* they will move more slowly toward the narrow ends, for the reason that the diameter decreases from the point *y* to the point *x* and therefore the extent of surface movement decreases.

In the modification shown in Fig. 13, the plunger is in the form of a plate 41 which is rigidly secured to a shaft 42; said plate being so constructed that its outer edge 43 increases its distance from the center of the shaft 42 throughout a portion of its length substantially in spiral form. This edge 43 is grooved or recessed as indicated by the dotted line 44 so as to register with the contour of the hairs and the shaft 42 may be rotated by any means so as to bring the grooved edge 43 in contact with a hair and thereby push the latter out of the hopper through the slot 9 to a pair of rollers or to any gripping or conveying means. If it is desired the shaft 42 may be oscillated instead of forming complete rotations but will in each case serve to push the hair out of its supporting means so as to be grasped and conveyed.

While I have shown and described a specific means for moving the plunger 15 and its equivalent, it will be noted that other means of operation may be employed without departing from the spirit of my invention. Also, the formation and construction of the several parts may be varied without departing from the idea of my invention,

as the latter consists of the broad idea of ejecting or pushing hairs or the like to a grasping or conveying means. Also, I have described and illustrated a particular form of guiding means, such as the extension 14 and the curved lower ends of the casing, the latter being clearly shown in Fig. 4, but it will be understood that any form of guiding means may be employed and, if it is desired, weight may be applied to the hairs while in the hopper so as to force them into the desired position.

I preferably dispose the hopper at an inclined angle, but it will be understood that the hopper may be placed in any other position if desired. Also, as illustrated the recesses on the plunger 15 and arm 35 and plate 41 are formed to engage only one hair at a time but they may be shaped to engage two or more hairs simultaneously if desired.

I claim:

1. The combination of a container for hairs and having a slot therein; gage means operable to permit the movement of a predetermined number of hairs toward the slot; means for separating hairs adjacent the slot from the other hairs in the container; and means for pushing the hairs through the slot.

2. The combination of a container for hairs having a slot therein; gage means operable to permit the movement of a predetermined number of hairs toward the slot for alinement therewith; means for separating hairs adjacent the slot from the other hairs in the container and for alining said separated hairs with the slot; and means for delivering the alined hair through the slot.

3. The combination of a container for hairs having a slot; a plunger; a gage member operable to permit the movement of a predetermined number of hairs into alinement with the slot; and means for moving said plunger into and out of said slot to successively deliver the alined hairs therethrough.

4. The combination of a container for hairs; a reciprocable plunger bar; a separator; means for moving the separator between the hairs to separate and thereby successively feed a certain number thereof into the path of the plunger; and means for moving the plunger to push said hairs from the container.

5. The combination of a container for hairs; a reciprocable plunger; a reciprocable separator; and means for alternately moving the plunger and the separator to successively feed the hairs into the path of the plunger so that they will be pushed thereby out of said container.

6. The combination of a hopper for supporting hairs or the like and having an inclined bottom, said hopper having a slot extending longitudinally through said bot-

tom at its lowest point; two rollers rotatable in opposite directions; and means operable to successively push hairs through the slot and between the said rollers, said slot having one end adjacent one end of the hopper and the other end extending over said rollers.

7. The combination of a hair container having an inclined bottom with an elongated slot therein extending in the direction of the incline; gripping rollers mounted below the slot; and means for successively pushing hairs through the slot between and into engagement with the gripping rollers.

8. The combination of a pair of gripping rollers; a container for supporting horse-hairs or the like having a slot formed therein and inclined to the lines of said rollers; a plunger adjacent the lower end of said container and movable through the slot therein; means for actuating the plunger to successively push hairs through the slot to the gripping rollers; and means for guiding the hairs into line with the slot prior to their engagement by said plunger.

9. The combination of a hopper for supporting hairs or the like having an inclined bottom; two rollers rotatable in opposite directions, said hopper being inclined and extending above and below the upper portions of the rollers, said hopper having a slot formed therein at the lower portion of the said inclined bottom, one end of said slot being at a point slightly above the lowest portion of the inner surface of the lower end of the hopper to form a shoulder for the lower ends of the hairs, the other end of said slot being vertically above the said rollers; a plunger; and means for actuating said plunger to successively engage hairs at points adjacent their lower ends and move them through said slot and between and into frictional contact with the said rollers.

10. The combination of a hopper for supporting hairs or the like having an inclined bottom; two rollers rotatable in opposite directions, said hopper being inclined and extending above and below the upper portions of the rollers, said hopper having a slot formed therein at the lower portion of the said inclined bottom, one end of said slot being at a point slightly above the lowest portion of the inner surface of the lower end of the hopper to form a shoulder for the lower ends of the hairs, the other end of said slot being vertically above the said rollers; a plunger; means for actuating said plunger to successively engage hairs at points adjacent their lower ends and move them through said slot and between and into frictional contact with the said rollers; and means for guiding said hairs into alignment with the said slot and into a position to be engaged by the said plunger.

11. The combination of a hopper for

supporting hairs or the like having an inclined bottom; two rollers rotatable in opposite directions, said hopper being inclined and extending above and below the upper portions of the rollers, said hopper having a slot formed therein at the lowest portion of the said inclined bottom, one end of said slot being at a point slightly above the lowest portion of the inner surface of the lower end of the hopper to form a shoulder for the lower ends of the hairs, the other end of said slot being vertically above the said rollers; a casing; a plunger mounted within said casing; and means for actuating said plunger to successively engage and move hairs adjacent their lower ends through said slot and between and into frictional contact with said rollers.

12. The combination of a hopper for supporting hairs or the like having an inclined bottom; two rollers rotatable in opposite directions, said hopper being inclined and extending above and below the upper portions of the rollers, said hopper having a slot formed therein at the lowest portion of the said inclined bottom, one end of said slot being at a point slightly above the lowest portion of the inner surface of the lower end of the hopper to form a shoulder for the lower ends of the hairs, the other end of said slot being vertically above the said rollers; a casing; a plunger mounted within said casing; means for actuating said plunger to successively engage and move hairs adjacent their lower ends through said slot and between and into frictional contact with said rollers; and means on said casing for guiding said hairs into alignment with the said slot in a position to be engaged by the said plunger.

13. The combination of a hopper; a pair of rotatably mounted rollers, said hopper having a slot formed therein, one end of said slot being adjacent the inner surface of one end of the hopper but slightly in advance of the same to form a supporting shoulder for the ends of the hair, the other end of said slot being vertically above the rollers; a plunger; and means for actuating said plunger to successively move hairs through said slot and between and into frictional contact with the said rollers.

14. The combination of a hopper; a pair of rollers rotatable in opposite directions, said hopper having a slot formed therein, one end of said slot being adjacent the inner surface of one end of the hopper but slightly in advance of the same to form a supporting shoulder for the ends of the hair, the other end of said slot being vertically above the rollers; a plunger; means for actuating said plunger to successively move hairs through said slot and between and into frictional contact with the said rollers; and means for guiding said hairs into alignment with the said slot and into a position to be engaged by the said plunger.

ment with said slot to be engaged by said plunger.

15. The combination of a hair container having a slot in its bottom; gripping rollers mounted below the slotted portion of the bottom with the lines of their adjacent portions parallel to the line of the slot; and means for pushing hairs through said slot and between said gripping rollers.
- 10 16. The combination of a hair container having an inclined bottom and provided with a slot extending in the direction of the incline; a pair of gripping rollers below

the slotted portion of said container bottom and mounted with the line of their adjacent 15 portions parallel to the line of said slot; and means for pushing hairs through said slot and between the rollers.

In testimony whereof, I have signed my name to this specification, in the presence 20 of two subscribing witnesses.

HERMAN RUDOLF SACK.
